United States Patent Office

Des. 180,851
Patented Aug. 20, 1957

180,851

BATHTUB

Wallace W. Stratton, Harper Woods, Mich., assignor to Active Tool and Manufacturing Company, Detroit,
Mich., a corporation of Michigan

Application November 7, 1955, Serial No. 38,765

Term of patent 14 years

(Cl. D4—4)

FIG. 1

FIG. 3

Fig. 1 is a perspective view of a bathtub embodying my new design.

Fig. 2 is a section taken on the line 2—2 of Fig. 1.

Fig. 3 is a section taken on the line 3—3 of Fig. 1.

The essential features of the bathtub are shown in solid lines.

I claim:

The ornamental design for a bathtub, as shown and described.
